CLAIM

The ornamental design for a vehicle tire pressure monitoring system, as shown and described.

DESCRIPTION

1. Vehicle tire pressure monitoring system

1.1 is a top view.

1.2 is a top perspective view.

1.3 is a front view.

1.4 is a back view.

1.5 is a left side view.

1.6 is a bottom view.

1.7 is a right side view.
